UNITED STATES PATENT OFFICE

MARY T. LUCAS, OF WHITESTONE, NEW YORK

FASTENER FOR INTIMATE BODY GARMENTS

Application filed September 18, 1929. Serial No. 393,722.

The invention relates to means for fastening corsets, brassières, and the like, and particularly to fastening means employing interengaging hook members and a slider for engaging and disengaging said hook members, and has for its principal object the provision of an improved construction of body garment by which the garment is entirely fastened by means of the fastener stated, the opening for the fastener extending into a strap secured to an edge of the garment, such for instance as a shoulder strap, or a suspending strap, so that the garment may be applied to the body by slipping it over the head or stepping into it preliminary to fastening it on the body.

The invention will be described in detail hereinafter and will be found illustrated in the accompanying drawings in which

Figure 1 is a front view in elevation of a corset having shoulder straps and showing the fastening means extended into one of the shoulder straps,

Figure 2 is a similar view of a type of corset not employing a shoulder strap and showing the fastening means extended into a depending tongue or strap, and

Figure 3 is an application of the device to a brassière.

In the drawings similar reference characters are used to designate corresponding parts throughout the several views.

In Figure 1 is shown a corset 1 having shoulder straps 2, and a fastening means for the corset comprising interengaging hooks 3 and a slider 4 for engaging and disengaging the hooks 3, this fastening means being of conventional type, the hooks 3 being secured on opposite sides of an opening in the garment as shown at 5 that extends into one of the shoulder straps 2, as shown at 6, so that when the slider 4 is moved upwardly near the extremity of the opening 6 in the strap 2, the parts 7 of the strap on opposite sides of the opening 6, being secured to the upper edge of the corset 1 will permit the garment to open sufficiently to permit the wearer to put on or take off the garment by slipping it over her head or stepping into it. 8 indicates a strap secured as shown at 9 at one

side of the opening 6 adjacent to the lower edge of the corset 1, and 10 indicates a detachable fastener of conventional type to hold the strap 8 across the slider 4 when the corset is in closed position as shown in Figure 1, said strap 8 protecting the outer garment from contact with the slider 4. Straps 2^a on shoulder straps 2 are provided to engage the shoulder straps of outer garments with said straps 2 to hold such straps on the shoulders.

In Figure 2 is shown a type of corset 11 without shoulder straps, such as shown in Figure 1, in which a depending strap 12 is provided on the lower edge of the corset and the interengaging hooks 13 that are actuated by the slider 14 in the manner hereinbefore stated in regard to the hooks 3 and slider 4 are secured on opposite edges of an opening 15 that is extended as shown at 16 into the strap 12, the edges 17 of the strap on the opposite sides of the opening 16 permitting a sufficient spread of the garment to permit it being put on or taken off. 18 indicates a strap secured at 19 at one side of the opening 15 and 20 a detachable fastener to secure the free end of the strap to the corset at the opposite side of the opening, said strap being provided to cover the slider 14 when the corset is fastened.

In Figure 3 is shown the fastening means applied to a brassière 21 having a strap 22 depending from its lower edge, and the interengaging hooks 23 that are operated by means of a slider 24 secured at opposite sides of the opening 25 in the body of the brassière and an extension of said opening shown at 26 in strap 22. The edges of the strap 22 at opposite sides of the opening 26 permit a sufficient spread of the garment to enable putting the garment on and taking it off, as hereinbefore stated in regard to Figures 1 and 2. 28 is a strap secured as shown at 29 to the garment and 30 a detachable fastener for securing the free end of the strap to the garment as hereinbefore described in regard to the straps 8 and 18.

What is claimed is:

A corset comprising a body portion, shoulder straps secured to the upper edge of said body portion, said body portion being

open on a line with one of said shoulder straps and the opening extending into the strap to provide for spreading the garment when unfastened to permit placing the garment on the person over the head or by stepping into it, interlocking members secured to the garment and strap at the opposite edges of said opening, said members being arranged in staggered relation, cam means slidably mounted on said interlocking members for actuating them into and out of locking engagement, a strap secured at one of its ends to the body portion adjacent to its lower edge, detachable fastening members secured to the body portion and the free end of the strap to secure the strap over the cam means when in position with the interlocking members engaged.

In testimony whereof I affix my signature.

MARY T. LUCAS.
